REFINER APPARATUS

Lionel M. Sutherland, Morrisville, Pa., assignor
to Sutherland Refiner Corporation, Trenton,
N. J., a corporation of New Jersey

Application May 2, 1951, Serial No. 224,121

7 Claims. (Cl. 92—26)

1

This invention relates to refiner apparatus, and more specifically relates to apparatus including a pair of opposed coacting relatively revolving refining members for refining pulp stock. The invention further concerns pulp refining discs of a character intended for incorporation in fiber pulp refining machines such as the apparatus represented in U. S. Patents Nos. 2,035,994, 2,156,320 and 2,156,321, for example.

The machines and refiner discs disclosed in the foregoing patents are capable of producing high quality pulp with low power consumption, and have enjoyed considerable commercial success. In such machines the discs have been provided with radially extending grooves, or with other non-radial grooves which extend outwardly from the center of the disc to a point adjacent its periphery. However, such grooves have conventionally been substantially semi-circular in cross section, and have therefore been substantially symmetrical with respect to the line perpendicular to the working face of the disc.

It has been discovered that improved refining results are obtained by providing relatively revolving pulp refining members the working faces of which include outwardly directed grooves having curved cross sections offset from the line perpendicular from such working faces, the grooves thus being of asymmetric character with respect to such perpendicular line. The offset grooves of the respective relatively revolving members are found to coact with one another to rotate the pulp stock as it travels along the groove axes. This whirling action appears to induce fiber disposition crosswise to the grooves and to minimize fiber damage in the refiner. Accordingly a pulp of higher quality, as compared to the pulp produced in conventional refiners, is obtained.

It is accordingly an object of the invention to provide a mechanism for producing improved refined fibrous material. It is another object of the invention to provide relatively revolving pulp refiner elements for producing high quality fibrous material from fibrous stock. Other objects and advantages of the invention, including the simplicity and economy of the same, will appear in further detail hereinafter, and in the drawings whereof.

Fig. 1 represents a fragmentary face view of one quadrant of a revolving refiner disc constituting one embodiment of this invention;

Fig. 2 represents a sectional view taken as indicated by the lines and arrows II—II, which appear in Fig. 1;

2

Fig. 3 represents a fragmentary face view of one quadrant of a stationary refiner disc which is adapted to be disposed face-to-face with respect to the revolving disc represented in Fig. 1;

5 Fig. 4 represents a sectional view taken as indicated by the lines and arrows IV—IV, which appear in Fig. 3;

Fig. 5 represents a fragmentary enlarged sectional view of the refiner discs of Figs. 1 and 3, taken as indicated by the lines and arrows V—V which appear in Figs. 1 and 3; the revolving and stationary discs being arranged face-to-face;

10 Figs. 6—8 represent sectional views similar to Fig. 5, indicating the relative positions of the parts of the revolving and stationary discs in the course of operation of the apparatus; and

15 Figs. 9—12 represent sectional views, similar to Figs. 5—8, of a modified form of the invention.

It will be appreciated that the embodiments 20 of the invention selected for illustration in the drawings constitute preferred embodiments of the invention, and may be modified in many particulars without departing from the scope of the invention.

25 Referring now particularly to Figs. 1—4 of the drawings, the refiner elements 20, 20a are in the form of flat discs having working faces 21. Disposed non-radially along the working faces 21 are the elongate grooves 22 separated from one another by the intervening ridges 28. The 30 grooves 22 are disposed in groups and arranged at various angles on the face of the disc 20 substantially in the manner described in detail in my aforementioned copending U. S. application Serial No. 193,643, of which this application is a 35 continuation in part, and the disclosure of which is incorporated herein by reference. The elongate grooves 22 extend non-radially generally outwardly or toward the peripheries of the refiner discs 20, 20a.

40 The numbers 23, 24 designate inner and outer annular grooves in the working faces of the flat discs 20. The inner annular groove 23 divides the working face into inner and outer annular working sections 25, 26. The elongate grooves 22 45 of inner working section 25 are at an angle to the corresponding grooves 22 of the immediately adjacent portion of outer working section 26, as fully brought out in my aforementioned copending U. S. application Serial No. 193,643.

45 The revolving disc 20 (Figs. 1, 2) has a hub 27 at its center and a plurality of spaced-apart, relatively wide and deep radial passages 30. Radial passages 30 have inclined floors 31 which slope upwardly from hub 27 to annular groove 23.

50 The revolving disc 20 has a hub 27 at its center and a plurality of spaced-apart, relatively wide and deep radial passages 30. Radial passages 30 have inclined floors 31 which slope upwardly from hub 27 to annular groove 23. 55 Alternate ridges 28 of outer working section 26

periphery of said disc, said grooves having curved cross sections the axes of which cross sections extend at an angle to a line perpendicular to said working face, and to the plane of the working face.

3. A refiner comprising a pair of relatively revolving refining discs having adjacent coacting working faces substantially parallel to one another, each of said working faces including elongate non-radial pulp carrying grooves all extending outwardly in the direction of the periphery of the disc, means for introducing fibrous pulp suspension to the inner ends of said grooves and for withdrawing said fibrous pulp suspension from their outer ends, the grooves of the respective discs being similar as to size and shape but disposed at angles to one another, and said grooves having curved offset cross sections the axes of which cross sections are substantially parallel to one another and extend at an angle to the line perpendicular to the working faces, and to the plane of said working face.

4. A refiner comprising a pair of relatively revolving refining discs having adjacent coacting working faces substantially parallel to one another, each of said working faces including elongate non-radial pulp carrying grooves all extending outwardly in the direction of the periphery of the disc, means for introducing fibrous pulp suspension to the inner ends of said grooves and for withdrawing said fibrous pulp suspension from their outer ends, the grooves of the respective discs having curved offset cross sections, the axes of the cross sections of the grooves on one disc extending at an angle to the groove cross section axes of the other disc, all said axes being at substantially the same angle to a plane extending generally parallel to the working faces of the discs.

5. A fiber pulp refiner comprising relatively revolving pulp refining members having coacting adjacent working faces substantially parallel to one another, each of said working faces including a set of elongate grooves parallel to one another and extending outwardly in the direction of the outer edges of the working faces, said grooves having curved cross sections, one end of the curve being at the working face and

the other end spaced therefrom, and said grooves also having flat faces extending from said other end of the curve to said working face, said flat face being disposed at an angle to the working face and to a line perpendicular to said working face, means for introducing pulp suspension to the inner ends of said grooves, and means for withdrawing the refined pulp from the outer ends of said grooves.

10 5. In a pulp refiner, a pair of refiner discs having coacting adjacent working faces, one of said discs being stationary and the other revolving, said discs including elongate pulp carrying grooves directed outwardly on said working faces, at least some of the grooves of the revolving disc having in cross section a curved surface and a flat-surface, said curved surface forming an acute angle with the working face of the disc at the lagging edge of the groove, and said flat face and working face forming an obtuse angle at the leading edge of the groove.

15 6. In a pulp refiner, a pair of refiner discs having coacting adjacent working faces, one of said discs being stationary and the other revolving, said discs including elongate pulp carrying grooves directed outwardly on said working faces, at least some of the grooves of the revolving disc having in cross section a curved surface and a flat-surface, said curved surface forming an acute angle with the working face of the disc at the lagging edge of the groove, and said flat face and working face forming an obtuse angle at the leading edge of the groove.

7. A fiber pulp refiner comprising relatively revolving pulp refining members having coacting adjacent working faces substantially parallel to one another, each of said working faces including an annular groove and a plurality of outwardly non-radially directed grooves disposed on the working faces outwardly of said annular groove, ridges intervening said outwardly directed grooves, flat faces upwardly inclined on said ridges extending at an angle from the base of said annular groove to the level of said ridges, said outwardly directed grooves having curved cross sectional contours offset from a line perpendicular to said working faces.

LIONEL M. SUTHERLAND.
